UNITED STATES PATENT OFFICE.

ROBERT CALVERT AND RICHARD ENGLE, OF SULLIVAN, INDIANA.

FLY-ESCAPE FOR WINDOW-SCREENS AND SCREEN-DOORS.

1,116,991.

Specification of Letters Patent.

Patented Nov. 10, 1914.

Application filed October 21, 1912. Serial No. 727,000.

To all whom it may concern:

Be it known that we, ROBERT CALVERT and RICHARD ENGLE, citizens of the United States, residing at Sullivan, in the county of Sullivan and State of Indiana, have invented certain new and useful Improvements in Fly-Escapes for Window-Screens and Screen-Doors; and we do declare the following to be a full, clear, and exact description of the invention, such as will enable others skilled in the art to which it appertains to make and use the same.

This invention relates to improvements in fly escapes for screen doors or window screens.

One object of the invention is to provide a device of this character adapted to be applied to a screen door or to a window screen whereby flies or other insects will, by reason of their habit of crawling up a screen, find their way out, but cannot readily find their way in through the escape.

Another object is to provide a device of this character which may be applied to any form of existing screen, adjustable or otherwise and which will be simple, strong and durable in construction, efficient in operation and well adapted to the purpose for which it is designed.

With these and other objects in view, the invention consists of certain novel features of construction, and the combination and arrangement of parts as will be more fully described and claimed.

In the accompanying drawings; Figure 1 is an inner side view of a screen door showing the invention applied thereto; Fig. 2 is an outer side view thereof; Fig. 3 is a central vertical longitudinal section; Fig. 4 is a horizontal section taken on the line 4—4 of Fig. 3; Fig. 5 is a perspective view of the escape showing the manner in which the same is constructed to be applied to screen doors already formed or in use; Fig. 6 is a vertical section through a portion of the screen door showing the form of the invention illustrated in Fig. 5 applied thereto; Fig. 7 is an inner side view of the escape applied to an adjustable window screen. Fig. 8 is vertical cross sectional view of the same, taken on line 8—8 of Fig. 7.

In the embodiment of the invention as shown in the first four figures of the drawing 1 denotes the frame of a screen door, 2 denotes the wire netting forming the covering for the door, said netting terminating a

suitable distance from the upper end of the door frame and being secured to the outer edge thereof by the usual binding strips or cleats 3. The lower portion of the door may be braced and ornamented by cross bars or scroll work of any design. The upper portion of the door however is preferably clear of any obstruction and contains simply the wire netting covering together with our improved escape now to be described.

The escape comprises a guard or insect guiding member consisting of a piece or sheet of wire netting or other material 4 having a width corresponding to the width of the door and being of sufficient length to extend from the top of the door frame downwardly to a considerable distance below the point where the upper end of the wire netting covering 2 of the door terminates. The piece of netting 4 forming the escape has its side edges engaged with metal side strips 5 and its lower edge engaged with a metal binding strip 6. The strip 6 and the lower portions of the side strips 5 are preferably channel shaped or folded over onto the edges of the netting while the upper portion of the side strips are flat and with the upper portion of the side edges of the netting 4 are engaged beneath and secured to the outer edge of the door frame by netting fastening strips 3 as shown. In thus arranging the wire netting 4 the lower portion thereof which is bound by the strips 5 and 6 is disposed on the inner side of the wire netting 2 covering of the door and is arranged at a slight angle to form a flaring space between the lower portion of the netting 4 and the netting 2 forming the cover of the door, said space gradually decreasing in width toward the upper end of the netting 2 so that the space opposite the upper edge of the netting covering 2 is only wide enough to permit a fly to pass freely through the same. The inwardly extending lower end of the piece 4 of netting 4 is firmly held in position by metal lugs 7 which are preferably cut and bent upwardly from the metal side strips 5 of the escapement, said lugs being tacked or otherwise securely fastened to the inner sides 105 of the door frame as shown. In arranging the escapement as shown and described the upper edge of the netting forming the covering of the door is preferably left unbound, so that the rough edge formed by the projecting ends of the wires forming the netting will act as an obstruction to deter the en-

trance of flies through the outside between said edge of the netting and the escapement.

With my improved escapement applied to a door as herein shown and described it will be seen that when flies or other insects light on the inner side of the screen and crawl upwardly they will pass beneath the lower portion of the netting 4 of the escapement and will be guided upwardly thereby until they pass out through the space between the upper end of the wire netting 2 of the door and the netting 4 of the escapement.

In Figs. 5 and 6 of the drawings the escapement is shown as constructed and arranged ready for application to standard size doors already constructed and hung, and in this instance the escapement comprises side pieces 8 which may be formed of wood or metal and which are tapered or inclined on one edge from a point near their lower ends to their upper ends as shown. Secured to the flat outer edges of the side pieces 8 is a wire netting covering 9, the side edges of which are preferably bound by metal strips which are tacked or otherwise secured to the edges of the side pieces as shown. The lower end of the covering projects a slight distance below the lower ends of the side pieces and also has applied thereto a binding strip 10 on the inner upper edge of which and spaced from the inner side of the strip is a guard plate or strip 11 between which and the inner side of the binding strip 10 is formed a space adapted to receive the upper edge of the wire netting covering of the door as will be hereinafter more fully described.

Secured to the tapered or inclined inner edges of the side braces 8 is an inner wire netting covering 12, the side and lower edges of which are protected by binding strips 13, while the upper end thereof projects a suitable distance above the top of the outer netting covering 9 and the upper ends of the side pieces 8. The projecting upper end of the covering 12 is bent at a slight angle to the lower portion thereof and forms the upper portion of the covering of the door.

By arranging the coverings 9 and 12 as shown and described, it will be seen that a space will be formed between said coverings, said space decreasing gradually in width to the upper end of the covering 9 at which point only sufficient space is provided between the coverings to permit a fly to pass out. The coverings 9 and 12 of the escape are preferably braced and reinforced by a spring bracing rod or wire 14 which is bent into substantially triangular shape or to a shape corresponding with the space between the coverings 9 and 12, said rod having its upper ends turned outwardly to form hooks 15 which are engaged with the meshes of the coverings 9 and 12 and thus hold the rod in place. The rod 14 when constructed and

arranged as herein shown and described will prevent the space at the upper edge of the covering 9 from becoming closed or in other words will hold the coverings 9 and 12 in their proper relative positions.

In applying the last described form of the invention to a door which has been already constructed, the upper portion of the netting covering of the door is cut off and removed for a suitable distance down and in the opening formed by the removal of the cut off piece of netting is placed the escapement. In thus placing the escapement the guard plate 11 and binding strip 10 on the lower end of the covering 9 are engaged with the cut upper edge of the covering of the door, thus protecting said edge and holding the same and the lower end of the escape in place. When in this position the side pieces 8 are engaged with and secured to the inner edges of the door frame, while the extended or projecting upper end of the covering 12 forming the inner side of the escape is secured to the upper piece of the door frame as shown. When the form of the escape just described is applied to the door it will be seen that flies or other insects crawling up the inner side of the netting covering of the door will pass on up between the coverings 9 and 12 of the escape until reaching the upper edge of the covering 9 at which point the flies may escape as will be readily understood.

In Figs. 7 and 8 of the drawings the invention is shown applied to an adjustable window screen in which the parts of the escape are all properly arranged and secured to permit the screen to be immediately applied to windows of different widths and in which when the screen is adjusted the parts of the escape will also be simultaneously adjusted.

In the adjustable form of the invention shown in Figs. 7 and 8, 16 denotes the adjustable window screen which may be of the ordinary or any suitable construction, the same being shown in the present instance as consisting of a frame having side bars 17 to which are connected upper and lower cross bars 18 formed in overlapping adjustably engaged sections which are slidably connected in any suitable manner. To the sides and upper and lower bars of the screen frame are secured the covering 19 of the screen, said covering being formed in overlapping sections in the usual manner. The sections of the screen covering 19 terminate at their upper ends a short distance below the upper bar of the screen frame and form between said upper ends and upper bar an exit passage 20 through which the insects may escape. The edges of the upper ends of the sections of the covering 19 are suitably bound and strengthened by binding strips 21. The inner edges 13

of the sections of the covering 19 are also bound and strengthened by vertical binding strips 22 the upper ends of which are extended. The extended upper end of the binding strip of each of the sections of the covering is bent in an opposite direction and engaged with the binding strips 21 of the upper edges of the opposing sections of the covering, said oppositely bent upper ends of the binding strips 22 thus forming guiding members for the upper edges of the screen covering when the sections of the latter are adjusted.

The escapement as applied to the adjustable form of screen above described comprises a guiding member 23 constructed of wire netting or other suitable material and which is formed in overlapping adjustable sections having on their lower edges and ends binding strips 24. The upper edge of one of the sections of the guiding member is secured to one of the sections of the upper cross bar of the screen frame while the other section of the guiding member is secured at its upper edge to the other member of the upper cross bar of the screen frame. The sections of the guiding member when thus arranged have an overlapping sliding engagement and are adapted to be shifted inwardly and outwardly simultaneously with the movement of the sections of the screen.

The outer ends of the sections of the guiding member 23 are secured to the inclined or angular edges 25 of supporting and attaching strips 26 which are adapted to be secured in any suitable manner to the inner edges of the vertical side bars of the screen frame as shown. The strips 26 are secured to the inner edges of the side bars of the screen frame in such position that the ends of the tapered upper portion of the strips terminate at the upper edges of the sections of the screen covering so that the sections of the guiding member 23 will be spaced a slight distance from said upper edges of the sections of the screen covering thus providing an exit opening for the insects crawling up the inner side of the covering of the screen and through the gradually decreasing space between the sections of the guiding member 23 and the sections of the screen covering.

In order to hold the lower edges of the sections of the guiding member 23 in sliding engagement and to guide said lower edges of the sections when the latter are adjusted with the sections of the screen we provide a substantially U-shaped guide plate 27 which is secured to the lower binding strip of one of the sections of the guiding member in position to receive the lower edge of the opposing section of said guiding member. When the parts of the adjustable form of the escape are constructed and attached to

the sections of an adjustable screen as herein shown and described, it will be seen that it is simply necessary in applying the screen to a window to adjust the sections thereof in the usual manner which operation will simultaneously adjust the sections of the escape which is thus brought into operative position without additional labor or trouble.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described our invention, what we claim is:

1. An escape for door and window screens comprising side pieces having their inner edges tapered or gradually decreasing in width toward their upper ends, an outer covering secured to the outer side of said side pieces, an inner covering or guiding member secured to the inclined inner edges of said side pieces, whereby a space is provided between said side pieces and inner and outer coverings, said space gradually decreasing in width toward the upper end of the outer covering, said inner covering extending forwardly above the upper edge of the outer covering, and a combined binding strip and guard on the lower edge of said outer covering adapted to receive the upper edge of the screen covering, said screen covering terminating below the top of the screen frame to receive said binding strip and guard.

2. An escape for door and window screens comprising side pieces having their inner edges tapered or gradually decreasing in width toward their upper ends, an outer covering secured to the outer side of said side pieces, an inner covering or guiding member secured to the inclined inner edges of said side pieces, whereby a space is provided between said side pieces and inner and outer coverings, said space gradually decreasing in width toward the upper end of the outer covering, said inner covering extending forwardly above the upper edge of the outer covering, and a spring bracing member arranged between said inner and outer coverings, whereby the same are held in proper spaced relation.

3. A fly escape for adjustable screens comprising a guiding member formed in adjustably connected sections, the edges of said sections being secured respectively to the adjustable sections of the upper bar of the screen frame, means for connecting said guiding member sections to the screen frame and to support them in position above the

upper edge of the screen covering and separated from the inner side thereof, a guide plate secured to the lower edge of one of the sections of the guide member and adapted to receive the edge of the co-acting section, whereby said lower edges of the sections are slidably connected.

4. A fly escape for adjustable screens comprising a guiding member formed in adjustably connected sections, the edges of which are secured respectively to the adjustable sections of the upper bar of the screen frame, supporting and attaching members secured to the outer side edges of said sections and to the side bars of the screen frame, whereby said sections of the guiding member are supported in position above the upper edge of the covering of the

screen and separated from the inner side thereof to form a gradually tapering space 20 which opens on the outside of the screen, a guide plate secured to the lower edge of one of said sections of the guiding member and adapted to receive the edge of the co-acting section, whereby said lower edges of the sections are slidably connected, and binding strips arranged on said lower edges of the sections of the guiding member.

In testimony whereof we have hereunto set our hands in presence of two subscribing witnesses.

ROBERT CALVERT.
RICHARD ENGLE.
